SYLVESTER H. ROWLAND, OF BATH, MAINE.

SWITCH CONTROL.

Application filed May 14, 1927. Serial No. 191,344.

This invention relates to improvements in switch controls, particularly relating to the controls adapted for use with motors and other electrical devices.

5 An object of this invention is to provide a protection for switch contact elements against the destructive effects of the electrical arcs formed during repeated starting, stepping and the reversing operations.

10 A further object of this invention is to provide a switch control having a two-way or double throw quick make and break switch action, in which, by moving a handle in either direction, the switch blades will function to 15 complete full contacts with a quick snapping motion, and on restoring the handle to the first position, the contacts open with sufficient speed to out-distance the arc.

Other objects of this invention will appear 20 from the detailed description of the device and as disclosed in the single sheet of drawings herewith made a part of the application.

In the drawings—

Figure 1 illustrates a longitudinal and 25 cross sectional view of the switch control disclosing the different elements in assembled relationship.

Figure 2 represents a cross sectional view 30 of a coupling, taken along line 2—2 of Figure 1.

Figure 3 discloses a diagrammatic view of a rotary switch having connections to the lines and the control coils of a motor from a panel.

35 Figure 4 illustrates a diagrammatic view of a four pole reverse rotary switch having connections to the armature of motors.

Fig. 5 illustrates a sectional view disclosing the center notch and friction spring feature.

40 In the switch control, according to this invention, a turning shaft or stem 1 is provided having a suitable handle portion 2 keyed or otherwise fastened thereto as at 3. The stem 1 is adapted to be mounted within a suitable switch housing comprising preferably head and rear cap portions 4 and 5 and casing element 6 made of material common to switch control housing. Stop pins 7 and 8 are 45 fastened to the stem element 1 in such a manner that when the handle element 2 is turned to the left, the stop pin 7 will function to bring tension to bear against the free end 9 of the switch centralizing spring 10, thereby 55 turning the pin 8 away from the free end of

the spring 11. At the same time, pins 12 and 13 attached to a sleeve element 14, adapted to revolve freely on the stem or shaft portion 1, are moved away from and in contact with the stop pins 7 and 8; that is, on turning 60 the handle 2 to the left, as above noted, the stop pin 7 functions to wind up the end 9 of the centralizing spring 10, 9 and 10, the free end of the spring 10 being turned away from the pin 12 attached to the sleeve, and 65 at the same time will function to turn stop pin 8 away from the spring end 11, while a trip arm portion 15, also suitably keyed or attached to the shaft 1 and adapted to cooperate with a coupling portion 16, moves against 70 a stop lug 17 extending from the coupling 16. In this operation or movement, the spring end 11 has been held by the pin 13 which is attached to the sleeve portion 14. This sleeve element is mounted to turn freely 75 on the shaft or stem 1, and is connected preferably integrally to the coupling portion 16 by means of an arm extension 18. In order to give the coupling portion 16 a suitable retarding action, friction elements 19, such as 80 springs, are provided for retarding the portion 16 until the trip arm 15 engages the stop element 17 on the coupling 16, thereby allowing it to move past the center notch of the friction springs 19, at which time the stored 85 up energy or pressure in the switch centralizing spring 9, 10 and 11 against the pin 13, sleeve 14, arm portion 18, coupling 16, and a shaft 20, is released, and rapidly turns the 90 required number of degrees according to the location of the handle, stop and switch blade contacts.

The friction springs 19 may be omitted where dummy contacts are available, as shown in switch diagrams, and should be, when used, 95 of sufficient tension to retard the action until the strip arm 15 engages the coupling stop whenever the switch is thrown for either contact.

The inner end of the shaft or stem element 1 is adapted to be rotatably mounted in the coupling portion 16, while the inner end of the shaft 20 is adapted to be securely keyed to the coupling 16.

In turning the handle 2 to the left, as above noted, a handle centralizing spring 21, 22, and 23 is wound up for a full travel of the handle 2 as follows: shaft 1, frame or drum portion 24, and pins 25 and 26 turn to the left, pin 26 turns the spring end 23 away from the hold- 105 110

ing pin 27 which is attached to the casing or housing element 6. Pin 25 moves away from the spring end 21 leaving it held by pin 28 which is also attached to the housing portion 5 6. During the above movement, the switch contacts were made as above and remain thus until the handle is released, when the spring end 23 turns the pins 26, frame 24, shaft 1, and handle 2 to the center. In the meantime, 10 the left switch contacts are broken as follows: Shaft 1 functions to turn pins 7 and 8 to the right, the pin 8 tending to wind up spring end 11 of the switch centralizing spring 10, and moves the end 11 away from the pin 13. 15 The spring end 9 holding on pin 12 until the trip arm 15 engages the stop 29 of the coupling 16, thereby turning the shaft 20 and moving switch blades out of contact. As 20 pressure of contacts is released, the spring tension on the end 9 against pin 12 snaps the sleeve 14 around to center position with the shaft 1 and the handle 2, taking with it the arm element 18, the coupling 16, shaft 20, and the switch blades. A description of the throw of 25 switch handle from the center to the right would be a repetition of the above, which covers the function of the elements when the switch is thrown from left to center. To throw the switch from right to center would 30 entail the same action as described in throw from center to left.

In operation, this invention provides a switch control having means for obtaining a two-way or double throw quick make and break 35 switch action. The ordinary type of switch control, even though provided with a single centralizing spring on the handle, is dependent on constantly expert manipulation by the operator. It has been found that in practice 40 the operator unconsciously allows his pressure to relax sufficiently to just break contacts and hold the arc, or in jogging or in short duration of operation, the contacts are neither closed nor open sufficiently, resulting in heating, burning and failing contacts. To obviate 45 these difficulties, this invention provides a means whereby, on moving the switch handle in either direction, the switch blades will function to make a full contact with a quick 50 snapping motion, and on restoring the handle to center, the contacts open with sufficient speed to out-distance the arc. This result is accomplished in the main by providing two 55 separate moving members, one attached to the handle, and the other to the switch and connected by a centralizing spring through a sleeve loosely mounted on the handle shaft and a coupling on the shaft, a trip arm loosely mounted inside of the coupling and rigidly 60 connected to the handle shaft to actuate the coupling in either direction after energy has been stored in the centralizing spring. In addition, a second centralizing spring is provided to be wound up on the motion of the 65 handle in either direction.

In the construction of this switch control, the particular form and type of centralizing springs, pins and switches may be of any desirable material. Furthermore, substitutions and alterations may be made in the disclosure of the drawings and in the specification within the scope of the claims without affecting the merits of this invention. 70

The stop pins or lug elements may be of any suitable type, either integrally formed from 75 the stem, housing or sleeve portions or otherwise.

What I claim is:—

1. In a switch control, means for obtaining a two-way or double throw quick make and break switch action, comprising a housing, a rotatable stem element mounted therein, a sleeve portion mounted loosely on the stem, a centralizing spring windably mounted on the sleeve, stop elements suitably fixed 80 to the stem and sleeve for contacting with the ends of the spring in such a manner that the spring may be wound on the rotation of the stem in either direction, a trip arm fixed to the stem, a coupling member formed integrally with the sleeve portion, the inner end of the stem element being rotatably mounted therein, stop elements extending from the coupling member for cooperating with the trip arm and a shaft element rotatably mounted 85 in the housing and fixed at one end in the coupling. 90

2. In a switch control, means for obtaining a two-way or double throw quick make and break switch action, comprising a housing, a 100 rotatable stem element mounted therein, a sleeve portion mounted loosely on the stem, a centralizing spring windably mounted on the sleeve, stop elements suitably fixed to the stem and sleeve for contacting with the ends 105 of the spring in such a manner that the spring may be wound on the rotation of the stem in either direction, a trip arm fixed to the stem, a coupling member formed integrally with the sleeve portion, the inner end of the stem 110 element being rotatably mounted therein, stop elements extending from the coupling member for cooperating with the trip arm and a shaft element rotatably mounted in the housing and fixed at one end in the coupling, 115 means for retarding action until the trip arm 120 engages the stop elements on the coupling, consisting of friction resilient elements suitably positioned in relationship to the housing and coupling.

3. In a switch control, means for obtaining a two-way or double throw quick make and break switch action, comprising a housing, rotatable stem element mounted therein, a sleeve portion mounted loosely on the stem, a centralizing spring windably mounted on the sleeve, stop elements suitably fixed to the stem and sleeve for contacting with the ends 125 of the spring in such a manner that the spring may be wound on the rotation of the 130

stem in either direction, a trip arm fixed to the stem, a coupling member formed integrally with the sleeve portion, the inner end of the stem element being rotatably mounted 5 therein, stop elements extending from the coupling member for cooperating with the trip arm and a shaft element rotatably mounted in the housing and fixed at one end in the coupling, means for returning the rotatable stem 10 element to center or neutral position consisting of an auxiliary sleeve element within the housing, a secondary centralizing spring loosely mounted thereon, stop pins attached to the housing and auxiliary sleeve portion 15 for the purpose of engaging the ends of the secondary spring.

4. A switch control comprising two separate movable members, a handle or stem element, one of the members being attached to 20 the handle or stem element, the other member attached to the switch and centralizing connection, a sleeve loosely mounted on the stem, a centralizing spring being mounted thereon, a coupling element integrally located with 25 the sleeve, a trip arm loosely mounted in cooperation with the coupling and rigidly connected to the stem, thereby providing means for actuating the coupling in either direction after energy has been stored in the centralizing 30 spring.

5. A switch control comprising two separate movable members, a handle or stem ele-

ment, one of the members being attached to the handle or stem element, the other member attached to the switch and centralizing 35 connection, a sleeve loosely mounted on the stem, a centralizing spring being mounted thereon, a coupling element integrally connected with the sleeve, a trip arm loosely mounted in cooperation with the coupling 40 and rigidly connected to the stem, thereby providing means for actuating the coupling in either direction after energy has been stored in the centralizing spring, a second centralizing spring loosely mounted on the 45 member attached to the stem for returning the stem to central or neutral position.

6. A switch control comprising a plurality of movable members, a stem element, one member being attached to the switch connection, 50 a sleeve loosely mounted on the stem, a centralizing spring mounted on the sleeve, the sleeve having a coupling member integrally connected therewith, means for actuating the coupling in either direction after energy has 55 been stored in the centralizing spring consisting of a trip arm loosely mounted in cooperation with the coupling and rigidly connected to the stem and means for holding the actuated member against rotation until released. 60

In testimony whereof I affix my signature.
